APPARATUS FOR DETERMINING THE DEW POINT OF A VAPOUR PRODUCT

Robert F. Deniston, Mount Vernon, Ill., and Wendell P. Hawthorne, Augusta, Kans., assignors to Socony-Vacuum Oil Company, Incorporated, New York, N. Y., a corporation of New York

Application May 5, 1936, Serial No. 77,942

2 Claims. (Cl. 73—51)

This invention relates to a device for continuously testing the product of a continuously operating distilling, stabilizing, or fractionating device.

5 An object of this invention is to provide a device capable of association with a fractionating device to continuously observe the dew point, or temperature of total equilibrium vaporization of the product of such apparatus.

10 Another object is to permit the observation of such quality in such a manner as to permit it to be used for control of the operation producing the product. Other objects and advantages are possessed by this invention, some of which will be referred to hereinafter and some of which will be obvious to those skilled in the art.

15 While pertinent to all distillation operations in which the end boiling point of the product must be controlled to avoid the inclusion of materials heavier than desired, the discussion will be herein limited to motor gasoline for simplicity. Most of the desirable properties of gasoline are tied up with its end distillation point and its volatility. So great is the truth of this statement that fractionating equipment for the production of gasoline is practically always operated by the control of end boiling point on the one hand and total vapor pressure on the other. Methods for automatically observing, and recording total vapor 20 pressure and basing the control on that have been worked out for application to stabilizers and similar apparatus for the reduction of volatility or vapor pressure in excess of that desired. No simple method has as yet been presented for the 25 automatic control of end boiling point.

30 Methods at present used for the control of end boiling point involve periodic removal of a sample, manual distillation in a batch process—the A. S. T. M. distillation, interpretation of results, 35 and subsequent change of distillation conditions if the control test has shown this to be necessary. This method presents several difficulties. Considerable time elapses between tests, manual control is involved, and a chemist's time is required 40 for the distillation. The results of the test are not, in themselves, a direct measure of the characteristics desirable in the product. The nearest approach to automatic operation of which we are aware accomplishes automatic withdrawal and 45 analysis of sample, but leaves the entire interpretation of results and adjustment for correction just where it was before.

50 This invention is based upon the discovery that the dew point of a product may be continuously

observed in a convenient manner, and the control of equipment automatically accomplished thereby.

5 The dew point of a vapor is the temperature at which initial condensation occurs when a whole, completely vaporized sample is cooled. Conversely, when considering a material such as gasoline, which has a boiling range rather than a boiling point, it is the temperature at which a sample heated under non-vaporizing conditions, will just be 100% vaporized on releasing or "flashing." 10 The dew point is thus a comparatively sensitive measure of heavy material in the product. It has the advantage of having a direct physical significance. Carburetion in an internal combustion engine, or analogous operations, are in reality 15 "flash" vaporizations. The dew point, or 100% equilibrium flash vaporization point, is directly responsible for completeness of vaporization under any given conditions and easily correlated therewith. No other commonly observed property is so directly a measure of this valuable characteristic of gasoline. Vapor pressure alone is only part of the story, because vapor pressure is highly sensitive to percentage of highly volatile components, and relatively insensible to high 20 boiling components. A. S. T. M. distillation end point is not completely significant, because two 25 gasolines of the same end point will vary greatly in ability to be volatilized under given conditions because of variation in relative amount of lighter 30 components present. These two properties bear 35 upon each other and thus compel interpretation of results and prevent simple automatic control from observation of such properties. Dew point is the one determinable property which ties these things together, and when it becomes possible to continuously observe and record the dew point, it is possible to continuously control still conditions in a simple and convenient manner without 40 the necessity of an operator's interpretation of results.

45 We have devised an apparatus for continuously observing and recording the dew point and which lends itself to such control. In order that this device may be more readily understood, reference 45 is now made to the drawings attached to and made a part of this specification, in which Figure 1 shows the dew point apparatus and Figure 2 shows the manner in which it may be applied to still control.

50 In Figure 1, which is diagrammatic, 3 is a pipe through which the distillate product to be tested is introduced in condensed or partially condensed form to coil 4, placed in heating bath 5, which is filled with a suitable liquid and heated by 55

some convenient means, as by electrical heater 6. In this heater coil 6, the gasoline is heated to a temperature slightly above the highest dew point to be encountered, and consequently the effluent from coil 6 is slightly superheated vapor, which is led to coil 7, placed in vessel 8, which is likewise filled with a suitable liquid and heated by suitable means, as electrical heater 9 to a temperature just below the lowest dew point expected. Upon the lower end of coil 7 is placed trap 10, constructed as shown. Material uncondensed in coil 7 passes through trap 10 and is led from the apparatus by pipe 11. Material condensed in coil 7 falls from the lip 12 at the end of the coil upon pan 13, which is preferably constructed of nonmagnetic material, and which is attached to and supported by solenoid rod 14, mounted in pipe 15. If the temperature in coil 7 is below the dew point, liquid will constantly drip onto the pan 13. If the temperature in coil 7 is at the dew point, no liquid will drop on pan 13 and no evaporation will occur therefrom. If the temperature is above the dew point liquid will evaporate from the pan 13 to the gas stream. Thus, below the dew point, the pan regularly becomes heavier,—until it is filled. Above the dew point it regularly becomes lighter,—until empty. This change in weight of pan 13 is employed to regulate the temperature of the bath and indirectly to observe and record dew point. Any suitable mechanism may be used for this purpose. We prefer to employ an inductance bridge, since it enables us to dispense with moving parts, springs, etc., mounted in the vapor stream and exposed to possible gumming and corrosion. The inductance bridge consists of solenoid coils 16 surrounding solenoid core 14, which supports the pan, and solenoid coils 17 surrounding core 18. The inductance bridge is actuated by a source of alternating current 20, which also supplies the various heating services. Without considering in detail the makeup of the inductance bridge, which is well known, its properties are such that when actuated by alternating current as shown, the two cores are suspended at certain points as determined by their weights, the properties of the coils, etc., and any change in the position of one is followed by a corresponding proportional change in the position of the other. Thus, when coil 7 is below the dew point and pan 13 becomes heavy, core 14 moves down, and a corresponding movement of core 18 relayed by contacts 19 admits current to auxiliary heater 21. When coil 7 is above the dew point, pan 13 becomes lighter, and core 18 is correspondingly moved to cut out heater 21. The bath in heating vessel 8 and coil 7 immersed therein are thus kept at the dew point of the vapor analyzed, proportions of bath and coil being so selected that "hunting" is minimized. It is of course understood that while direct contacts are shown at 19, it will probably be preferable to employ some convenient form of relay system, the direct contacts being shown for simplicity. Since the bath in vessel 8 is maintained at the dew point of the substance analyzed, it is simple to observe the temperature of the bath or in the trap 10 by any convenient form of thermocouple as 22, here shown in the bath near trap 10, to which is attached the indicating and recording pyrometer designated by 23.

Figure 3 shows in diagrammatic form how this determination of dew point, in this apparatus may be utilized for the control of a distillation operation. In Figure 2, 24 is a columnar still, to which feed is introduced by pipe 25, and heated by steam coil 26. Residue is withdrawn through pipe 27, and vapors pass overhead through pipe 28 and condenser 29 to receiver 30. Distillate product is withdrawn through pipe 31, and pipe 32 is provided to lead a continuous sample of distillate to a dew point analyzer comprising vessels 5 and 8 and trap 10, as previously described. Here again, thermocouple 22 observes the dew point and instrument 23 indicates and records it. In this set-up however, instrument 23 has an additional function. Condensate from drum 30 is returned by pump 33 through pipe 34 as wet reflux, for control of top temperature of tower 24, the volume returned being controlled by valve 35. Instrument 23 in this case is also a control instrument, so designed that when the dew point observed exceeds a predetermined maximum, more reflux is admitted to tower 24, and when the dew point becomes too low, less is admitted. Control instruments capable of so acting are common, well known, and of many forms, and their details are no part of this invention, and the control function is consequently indicated by the dotted connection between instrument 23 and valve 35.

It is realized that equivalents of the device herein disclosed will occur to those skilled in the art, and it is our intention to claim all that is novel therein, except as limited by the following claims.

We claim:

1. Means for continuously observing the dew point of a continuously flowing stream of vaporizable substance comprising means for continuously sampling said stream, means for converting said sample to a slightly superheated vapor, a tube through which said vapor flows, a heater to maintain said tube at a temperature below the dew point of said vapor, said tube including a trap, a pan in said trap, means to direct condensate formed in said tube on said pan, an auxiliary heater for said tube, means responsive to the weight of the condensate in said pan to control said auxiliary heater to add more heat in response to an increase and less heat in response to a decrease in condensate, whereby said tube is maintained at the dew point temperature of said vapor, and means to observe the temperature of the tube.

2. Means for continuously observing the dew point of a flowing stream of vaporizable substance, comprising means to extract a sample therefrom, means to convert such sample to a slightly superheated vapor, means to cool such vapor to a controlled temperature, means to collect any condensate so formed in a position exposed to uncondensed vapors, means actuated by the amount of condensate collected to so control the cooling temperature that the condensate amount tends neither to decrease nor increase, and means to observe the controlled temperature.
